DESIGN FOR A STORE FRONT

Milton J. Bluestein, New York, N. Y., assignor to Plymouth Shops, Inc., New York, N. Y., a corporation of New York

Application February 15, 1936, Serial No. 61,188

Term of patent 14 years

To all whom it may concern:

Be it known that I, Milton J. Bluestein, a citizen of the United States, residing at New York, county and State of New York, have invented a new, original, and ornamental Design for a Store Front, of which the following is a specification, reference being had to the accompanying drawing, forming a part thereof.

In the drawing:

Fig. 1 is a perspective view of a store front showing my new design.

Fig. 2 is a horizontal sectional view on line 2—2 of Fig. 1.

I claim:

The ornamental design for a store front substantially as shown.

MILTON J. BLUESTEIN.
